Des. 215,443
Patented Sept. 30, 1969

215,443

ROTARY SWITCH STATOR UNIT

Kenneth C. Allison, 1540 Lake Shore Drive,
Crystal Lake, Ill. 60014

Filed Sept. 25, 1968, Ser. No. 13,704

Term of patent 14 years

Int. Cl. D13—03

U.S. Cl. D26—13

FIG. 1 is a front elevational view of a rotary switch stator unit showing my new design.

FIG. 2 is a rear elevational view thereof.

FIG. 3 is an edge view thereof.

FIG. 4 is a sectional view taken along line 4—4 of FIG. 1.

FIG. 5 is a sectional view taken along line 5—5 of FIG. 1.

The dominant features of my design reside in the portion shown in full lines in the accompanying drawing.

I claim:

The ornamental design for a rotary switch stator unit, as shown and described.
